UNITED STATES PATENT OFFICE.

DANIEL WOODHEAD, OF EVANSTON, ILLINOIS.

MOUNTING FOR TRANSLATING DEVICES.

1,269,355.

Specification of Letters Patent. Patented June 11, 1918.

Application filed May 28, 1917. Serial No. 171,354.

To all whom it may concern:

Be it known that I, DANIEL WOODHEAD, a citizen of the United States, residing at Evanston, in the county of Cook and State 5 of Illinois, have invented a certain new and useful Improvement in Mountings for Translating Devices, of which the following is a specification.

My invention relates to mountings for 10 electric translating devices and is particularly applicable to railway passenger cars in which the seats or berths are arranged in sections separated by partitions extending from the side in toward the center of the 15 car. The principal object of the invention is to provide means whereby an electric translating device, notably an electric fan, may be utilized in such a situation in a practical and economical manner. It will 20 be understood that in sleeping cars, for example, ventilation is always a more or less difficult problem, especially in hot weather, and at night when the head boards are up. According to my invention, I provide a 25 tilating fan for each section and provide means whereby a single fan is made to serve either one of two adjacent sections. The advantage of this is that with but a single fan to a berth, the breeze may always 30 be made to come from the foot of the berth. It is common practice to make up the berths in such manner that the occupant will always have his head toward the engine. In consequence of my invention, the fan will 35 always be at the feet of the occupant and yet it is necessary to provide but one fan for each pair of berths. The contributory objects of the invention are to carry out the plan economically, simply, and without 40 marring the appearance of the car or lessening the privacy in each section.

These objects are accomplished by the construction illustrated in the accompanying drawings, in which:

45 Figure 1 is a face view of a partition and the adjoining portions at the upper berth of a sleeping car equipped with mechanism embodying the invention.

Fig. 2 is a plan section on the line 2—2, 50 Fig. 1.

Fig. 3 is a plan section on the line 2—2, Fig. 1 but drawn on a smaller scale and showing two complete adjoining upper berths.

55 Fig. 4 is a view similar to Fig. 1, but drawn on a larger scale and shown partly in

section to reveal the wiring, the mountings of the panel which supports the fan, and the locking mechanism for preventing rotation of the panel.

60

Fig. 5 is a sectional view on the line 5—5, Fig. 4.

Fig. 6 is a plan section of the lower trunnion and associated parts on the line 6—6, Fig. 4.

65

Fig. 7 is an elevation of the lower trunnion and associated parts.

Similar numerals refer to similar parts throughout the several views.

In the form selected to illustrate the invention, a conventional sleeping car construction is shown. It will be sufficient for the present purpose to say that the car has an outer shell 1 and inner shell 2 at the roof and upper portion of the sides. Between each section there is a partition consisting of a fixed portion 3 and a removable portion 4. It will be understood that the removable portion, commonly called the "head board", is only used at night, being removed and stowed away in the daytime. While I have illustrated only the construction of the upper berth it will be understood that a similar construction may be repeated for the lower berth. The berth proper 5 is hinged to the side of the car and when lowered is supported at each end by chains or cables 6.

The details for carrying out the invention may be considerably varied, and attention is called to my copending application, Ser. No. 172,592, filed on the fourth day of June, 1917.

In the form here shown, the stationary portion of the partition has a circular aperture 8 into which fits a panel 9. This panel is rotatable about a vertical axis and has an upper trunnion 10 fitting

95 into a socket 11 in the fixed part of the partition. The lower trunnion 12 is in the form of a sleeve partially embedded in the panel, as best shown in Figs. 4 and 5. At

100 the bottom, this sleeve projects into a socket 13 countersunk into the fixed part 3 of the partition. By preference, an annular flange 14 is formed on the sleeve to constitute a step bearing or wearing plate to rotatably support the panel upon the partition. The

105 socket 13, being let into the partition from the surface thereof, facilitates assembly of the parts and also prevents the dismounting 110 of the panel from its trunnions except by the aid of a screw driver or other tool for

removing the fastening devices which hold the lower socket in place. The panel is prevented from rotating more than 180 degrees by means which, in the present case, 5 are located in and form part of the lower trunnion and are best understood by reference to Fig. 6. In this case, a lug 16 is formed on the side of sleeve 12 and this engages a stop 17 formed in socket 13.

10 The fan 20 is mounted on one face of the panel 9 and is supplied with electric current through conductors 21 which lead in through the inner shell 2, thence through a conduit 22 embedded in the partition, as 15 best shown in Figs. 4 and 5. They pass thence through sleeve 12 up through the chambered panel and thence to the fan. As the rotation of the panel is limited to 180 degrees, or thereabout, no sliding contacts 20 are necessary and the supply conductors themselves lead from the immovable to the movable parts without danger of damage. It will be obvious that by rotating the panel, the fan may be made to deliver into 25 either one of the two adjacent sections.

In order to make it impossible to rotate the panel when the berths are made up, I have provided automatic locking means which are inaccessible from either berth.

30 These means are best shown in Figs. 1, 2, and 4. A locking rod 25 is slidably mounted in a tube 26 embedded within the stationary part 3 of the partition. The inner end of this rod is capable of entering into 35 either one of the sockets 27 formed in the edges of the panel 9. A spring 28 normally holds this locking rod in non-operative position, so that the panel may be rotated. But the head board 4 or movable 40 part of the partition is provided with a stud 29, which, when the head board is in position, enters the tube 26 and forces the head 30 of the rod inward, thus holding the rod in acting position. Consequently, 45 the panel cannot be released without removing the head board. During the day time the locking rod may be held in acting position by the pin 31 which slides in the slot 32 formed in the side of the partition, 50 as shown in Fig. 4. Slot 32 has a suitable lateral notch (not shown) at the inner end, for retaining pin 31.

In operation, when the porter is ready to make up the berths, he decides where 55 the head of the occupant will lie. He then turns the panel 9 so that the fan will be exposed at the foot end of the berth. As soon as he positions the head board 4, the panel will become securely locked in place 60 and it will remain locked until the head board is removed. The panel, as it completely closes the opening 8 in the partition, renders each berth as private as if the partition were imperforate.

65 As a result of this construction, there is

a fan available for each berth and the fan may always be located at the foot of the occupant and yet, except for the end berths in the car, the number of fans does not exceed the number of berths. The wiring 70 is all "blind," that is, invisible, and there are no sliding contacts to form a source of trouble. The appearance of the car is not detracted from and the security and privacy of each berth is not interfered with. 75

Having thus described my invention, what I claim as new and desire to secure by Letters Patent, is:

1. In apparatus of the class described, a partition having an aperture in it, a flat imperforate panel closely fitting said aperture and capable of facing either way, and an electric translating device mounted wholly on one side of said panel whereby the translating device may exert its effect in either 85 direction from the partition and vision through the aperture will be totally cut off.

2. In apparatus of the class described, a partition having an opening within its borders, a flat panel closely fitting said opening 90 and pivoted on trunnions centrally located with respect to the panel whereby it may be rotated 180 degrees so as to lie flat with the partition and face either way, the panel being adapted to cut off vision through the 95 opening, and an electric translating device mounted wholly on one side of said panel for the purpose described.

3. In apparatus of the class described, a partition having an opening within its borders, a flat panel closely fitting said opening and pivoted on trunnions centrally located with respect to the panel whereby it may be rotated 180 degrees so as to lie flat with the partition and face either way, the panel 100 being adapted to cut off vision through the opening, and an electric translating device mounted wholly on one side of said panel for the purpose described, one pair of trunnions being hollow and having the electric 105 conductors passing up through it whereby the translating device may be energized when the panel is in either of its positions flush with the partition.

4. In apparatus of the class described, a 115 partition having a fixed and a removable portion arranged in the same plane, the fixed portion having an aperture in it, a panel mounted in said aperture and being imperforate through 180 degrees and being 120 imperforate to thereby exclude vision through the partition when facing either way and lying in the plane of the partition, an electric translating device mounted wholly upon one side of the panel, and locking means 125 operated by the removable portion of the partition for locking the panel in either one of its positions flush with the partition.

5. In a passenger car, in combination, a partition between sections, said partition 130

having a hole in it, a panel closing said hole, an electric translating device mounted on one side only of said panel, trunnions connecting the panel with the partition, and 5 electric conductors passing through one of said trunnions to energize said translating device, whereby the panel may be reversed without disturbing the electric wiring.

6. A passenger car having partitions between the sections, the partition having a fixed and a removable portion, one of said portions having an aperture passing through it, an electric translating device, a support for said device, said support being movably mounted in said aperture, and means operated by the removable portion of said partition for locking said support against movement.

7. A passenger car having partitions between the sections, the partition having a fixed and a removable portion, the fixed portion having a hole extending through it, a ventilating fan, a support for said fan mounted in the hole and being movable to present the fan at one side or the other of the partition, and means operated by the removable portion of the partition for locking said support against movement.

8. A passenger car having partitions between the sections, the partition having a fixed and a removable portion, the fixed portion having an aperture, a fan, a support for closing said aperture, said support being rotatable to present the fan toward one or

the other of the sections, a locking device in 35 the fixed portion of the partition for preventing rotation of the support, said locking means being normally non-operative, and means operated by the removable portion of the partition for holding the locking 40 means in operating condition.

9. A passenger car having partitions between the sections, the partition having a fixed and a removable portion, the fixed portion having an aperture, a fan, a support 45 for closing said aperture, said support being rotatable to present the fan toward one or the other of the sections, a locking rod mounted in the fixed portion of the partition for preventing rotation of the support, 50 a spring for normally holding said rod out of engagement with the support, and means operated by the removable portion of the support for holding said rod in engagement with the support.

10. A passenger car having partitions between sections, each partition having an aperture, a panel in the plane of the partition, said panel filling the aperture in the partition, an electric fan on one side of said 60 panel, trunnions for rotatably supporting said panel, one of said trunnions being hollow, and electric conductors passing through the hollow trunnion to the fan for energizing it.

In witness whereof, I have hereunto subscribed my name.

DANIEL WOODHEAD.
